CARPENTER'S MEASURING TOOL

Filed April 30, 1923

2 Sheets-Sheet 2

UNITED STATES PATENT OFFICE.

PETER WALDO ZOOK, OF URBANA, ILLINOIS.

CARPENTER'S MEASURING TOOL.

Application filed April 30, 1923. Serial No. 635,726.

To all whom it may concern:

Be it known that I, PETER WALDO ZOOK, a citizen of the United States, and a resident of Urbana, in the county of Champaign and State of Illinois, have invented new and useful Improvements in Carpenters' Measuring Tools, of which the following is a full, clear, and exact description.

My invention relates to improvements in carpenters' measuring tools, and it consists in the combinations, constructions, and arrangements herein described and claimed.

An object of my invention is to provide a device of the character described by means of which the exact length of common rafters after each one-half inch rise above a five inch rise, and the length of the hip or valley for the same rise, at any desired pitch from zero to twenty four inches may be instantly calculated. In the ordinary type of device, it would be necessary to employ a square of extremely great length to accomplish this result, but in my present invention, I have devised a novel means for accomplishing the result with a square not larger than the ordinary two-foot steel square in common use in carpentry.

A further object of my invention is to provide a device of the character described by means of which the difference in length of the jacks for the rafters at predetermined centers may be simultaneously calculated with the length of common rafter.

A further object of my invention is to provide a device of the character described in which certain of the measuring blades may be reversed, and upon which the exact side cut for the jacks, or the side cut for the hip or valley, may be determined.

A further object of my invention is to provide a device of the character described which makes use of the ordinary carpenter's two-foot steel square as a separable part of another device.

A further object of my invention is to provide a device of the character described by means of which taper cuts readable in inches per foot run for a given angle, may be instantly read. The latter feature is most important in determining such measurements as are necessary to construct a smoke stack, column, or the like.

Other objects and advantages will appear in the following specification, and the novel

features of the invention will be particularly 55 pointed out in the appended claims.

My invention is illustrated in the accompanying drawings, forming part of this application, in which

Figure 1 is a side elevation of an embodiment of my invention,

Figure 2 is a sectional view along the line 2-2 of Figure 1,

Figure 3 is a sectional view along the line 3-3 of Figure 1,

Figure 4 is a fragmentary view of a portion of the mechanism illustrated in Figure 1,

Figure 5 is a view of the reverse side of the pivotal blade illustrated in Figure 1,

Figure 6 is a view of the mechanism illustrated in Figure 1 with the auxiliary rule and blade applied thereto, and

Figure 7 is a sectional view along the line 7-7 of Figure 6.

In carrying out my invention, I make use of the ordinary type of carpenter's two-foot steel square 1 calibrated in inches at the outermost edges 2 and 3 thereof. A metal protractor 4, preferably of steel, is constructed 80 with an integral socket 5 on one side of the base portion 6 arranged to receive the shorter of the two sides of the steel square (see Figure 2) so that the protractor and the square, when assembled, will have the appearance shown in Figure 1, that is, with the remote edge 7 of the protractor at the twelve inch mark on the shortest side of the square.

The protractor 4 is provided with a downwardly extending wing 8 at the remote end 90 of its base portion 6, which wing has a slot 9 punched therethrough terminating at its upper end in an enlarged circular recess 10. The protractor 4 is provided with an arcuate slot 11 therethrough concentric with the 95 graduated scale 12 thereof, the scale 12 being graduated in degrees from zero degrees to ninety degrees. This scale 13 is disposed adjacent to the upper edge of the slot 11.

A steel blade 14 is provided with a pair 100 of mushroom buttons 15 at its lowermost end, one on each side thereof and at the right hand edge of the blade. The head of this mushroom button is arranged to pass through the enlarged recess 10 in the wing 105 portion 8 so that the stem of the button 15 may enter the slot 9 and the head of the button prevent dislodgment thereof from the

slot when the stem is at the lowermost portion of the slot. The blade 14, the reverse side of which is illustrated in Figure 5, is provided with a substantially rectangular opening 16 therethrough in registration with the slot 11 when the stem of the button 15 is at the lowermost portion of the slot 9. A binding thumb nut 17, having a rectangular work engaging surface 18 arranged to pass through the opening 16 when in registration therewith, is provided for clamping the blade 14 against movement relative to the protractor 4. This end is accomplished by the provision of a second clamping member 19 having a threaded bore 20 therethrough arranged to engage with a threaded stem 21 which projects inwardly from the surface 18 of the nut 17. Obviously, when the nut 17 is turned to the position shown in Figure 3, the blade 14 may not move away from the protractor, but when the nut 17 is turned a quarter of a turn to the left, the flange 18 will permit the outward movement of the blade 14, since the flange is then in registration with the opening 16 and consequently permitting movement of the blade 14.

Each side of the blade 14 is divided longitudinally into four sections, and legends having predetermined values are disposed in each of the columns so formed. The first column 22 bears legends designating length of common rafter for each one-half rise above five inches up to twenty four inches. The second column bears legends designating length of hip or valley rafter for each one-half rise above five inches up to twenty four inches. The third column 24 bears legends designating the difference in length of jacks, sixteen inch centers, while the fourth column 25 bears legends designating the difference in length of jacks, twenty four inch centers.

The reverse side of the rule 14 is also divided longitudinally into four columns. The first column 26 thereof bears legends designating the side cut for jacks. The second column 27 bears legends designating a side cut sheet for hip or valley. The third column 28 bears legends indicating the side cut for hip or valley ridge, and the fourth column 29 bears legends designating the side cut sheet for hip or valley ridge.

It is apparent from the illustration in Figure 1 that great difficulty would be had in calculating measurements for relatively high pitch, and that this would necessitate the use of a steel square of extraordinary length which of course would be too cumbersome to permit the use thereof. I therefore have devised a novel construction in the provision of an auxiliary rule by means of which measurements for relatively high pitches may be accurately read. This auxiliary rule is indicated at 30 and has

the side walls of its outer ends 31 and 32 beveled and arranged to fit into a dovetail slot 33 in the rear wall of the protractor 4 (see Figure 7). The rule 30 is marked off on one side with legends having values from 25 to 48, and on the other side and readable from the reverse direction with legends having values from 49 to 96. It will be seen therefore that this auxiliary rule when used may take the place of a steel square having a length of substantially eight feet on one side. It will be noted that the legends from 25 to 28 are substantially closer together than the legends on the steel square, and that the legends from 49 to 96 are closer together than those designating values from 25 to 48. In Figure 6 I have shown the auxiliary rule 30 in use and set so that the legends having values from 25 to 48 may be employed. The dovetail socket 33 has its right hand wall in exact registration with the six inch mark on the short side of the steel rule 2, or on a mark provided on the protractor 4 indicating the six inch position of the square. If the auxiliary rule 30 is to be reversed, the legends having values from 49 to 96 to be employed, then it is inserted in a dovetail socket 34 having its right hand edge in exact registration with a nine inch mark on the steel square 1 or in registration with a mark on the protractor designated in the position of the nine inch mark of the steel square if the square be absent.

Obviously it is necessary to employ blades similar to the blades 14 but calibrated in higher values for use with each of the two sides of the auxiliary rule 30. Such a blade is provided at 35 Figure 6 in which only one side of the blade is illustrated, since the opposite side of the blade is calibrated in legends similar to the legends illustrated in Figure 5, but of higher values. There are two of the auxiliary blades, one of them illustrated at 35 and another indicated in dotted lines at 36. The blade 36, like the blade 35, is calibrated in values which read properly when used in conjunction with the reverse side of the rule 30. The protractor 4 has a horizontal scale 37 thereon bearing legends indicating the slope of a straight edge per foot at any degree. This scale 37 is substantially six inches from the edge 3 of the steel rule 1, and therefore one-half inch equals one inch on the scale 37.

From the foregoing description of the various parts of the device, the operation thereof may be readily understood. With reference to Figure 1, let us assume that it is desired to obtain certain measurements for roof construction or the like, and that the pitch is one-half pitch or 45 degrees. In this event, the blade 14 will be moved to the position shown in Figure 1, and the thumb nut 17 tightened. It will be noted that the

left hand edge of the rule 14 is therefore in registration with the twelve inch marks of the sides 2 and 3 of the steel square 1. The length of the common rafter readable in the 5 column 22 of the blade 14 is therefore 16.97 inches and the length of the common hip or valley is 20.78 inches. This is read above the line which is in registration with the mark twelve inches on the side 2 of the steel 10 square 1. To calculate from this reading the exact length of any rafter, the carpenter must multiply the run of the rafter; i. e., one-half the width of the building, by the reading shown in columns 22 and 23. Let 15 us say the building is sixteen feet wide. The run is therefore eight feet. 16.97 as shown on the blade 14 for a one-half pitch is therefore multiplied by 8, which will give 135.96 inches, which reduced to feet is approximately 11 feet, 4 inches. This then will be the actual length of the rafter.

For the length of the hip or valley, the reading 20.78 is multiplied by 8, which equals 166.24 inches, or substantially 13 feet, 11 25 inches. 13 feet, 11 inches will therefore be the exact length of the hip or valley.

Let us assume now that it is desirous to know the dimensions which the jacks or rafters are to be cut, and that these jacks 30 are upon sixteen inch centers. The reading in column 24, which is for sixteen inch centers, is $22\frac{1}{2}$ inches, which means that the first set of jacks is $22\frac{1}{2}$ inches shorter than the preceding sets until all are cut. If, however, the jacks are to be used on twenty-four 35 inch centers, then the reading of the column 25, which is for twenty-four inch centers, indicates that the jacks must be cut 34 inches shorter than the preceding sets until all sets 40 are cut.

Let us now refer for further information in this same problem to the opposite side of the rule. This may be done by unfastening the thumb nut 17 and drawing the flange 45 18 out of engagement with the outer face of the blade 14. When this is done, the blade 14 may be raised so that the stem of the mushroom button 15 may be moved up into the enlarged recess 10 of the slot, and the blade removed. The blade is then reversed 50 and the button 15 on the opposite side of the blade is inserted into the recess 10 after which the stem thereof is moved downwardly into the slot, and the thumb nut 17 adjusted to lock the blade 14 into registration 55 with the mark 12 on the long side of the steel square 1. This side of the blade is shown in Figure 5, and our first reading will be in columns 26 and 27. It will be noted 60 that the line indicated at X will fall into registration with the mark 12 and the legends above this line and for columns 26 and 27, are 17 and 12 inches, respectively. The values designated by the legends in 65 columns 26 and 27 above the line X are for

the side cut of the jacks. The side cut for the hip or valley at ridge, will be found in columns 28 and 29, and in this particular case are $20\frac{1}{8}$ inches, and 17 inches, respectively.

Let us assume now that the work upon which dimensions and measurements are necessary is work requiring a pitch greater than the blade 14 is capable of reaching. In this event, the blade 14 is removed from the protractor 4 in the manner heretofore described and the blade 35, which is precisely the same, except that the blade 35 has higher values, is moved into its place, and the auxiliary rule 30 is moved into its respective socket 33 with that side bearing legends designating values from 25 to 49 toward the right. The operation of the blade 35 on the auxiliary rule 30 is precisely the same as the blade 14 on the long side 2 of the steel square. It is therefore thought to be unnecessary to describe such operation in detail.

The blade 35, however, is not capable of reading for a greater pitch which is the greatest pitch that the mark 48 of the auxiliary rule 30 indicates, and if higher values are wanted, that is work requiring a higher pitch, it will be necessary to withdraw the auxiliary rule 30 from the socket 33, reverse the rule, and insert it in an inverted position in the socket 34, whereupon a third blade 36, having values higher than the blade 35, is inserted upon the protractor 4 in the manner heretofore described.

Let us assume that it is desired to figure accurately the exact taper of a straight edge in inches per foot of a stack, say 89 degrees. To this end, any one of the three blades 14, 35, or 36 may be employed, and the blade moved so that its left or upper edge is in registration with the mark of the protractor scale 12. The reading in taper of the straight edge in inches per foot may be read directly upon the scale 37 Fig. 6.

Another important use of my improved carpenter's measuring device is for determining the relative length and size for polygonal cuts. Let us say that it is desired to cut miter cuts for a four sided figure, i. e., a square. 180° as divided by 4 is equal to 45 degrees. Any one of the blades may be used and is set with its upper edge in registration with the 45 degree mark on the protractor scale 12. The reading upon the lengths 1 and 3 of the square will be 12—12. In other words, the pivotal center of the blade is 12 inches on one side of the square and the blade intersects the remaining side of the square at the 12 inch mark.

Let us say now that it is desired to cut the miter for an 8 side figure. 180 degrees divided by 8 is equal to $22\frac{1}{2}$ degrees. If the blade is then moved on its pivotal center to $22\frac{1}{2}$ degrees on the protractor scale, the reading on the longest side of the square 130

will be approximately 5 inches. The cut will therefore be a miter having 5 inches for one side and 12 inches for the other.

I claim:

5. 1. The combination with a carpenter's square and a protractor disposed with its quadrant intermediate the adjacent sides of said square, of a blade having longitudinally disposed columns of legends designating 10 measurements relevant to carpentry arranged to be pivotally supported on an axis common with the axis of said quadrant, whereby said blade may cross one of the sides of said square when said blade is set 15 with its edge at certain points on said quadrant, the legends on said blade at the intersecting point of said blade and said side of said square designating measurements relevant to the pitch at which said blade is 20 set relevant to said quadrant.
2. The combination with a carpenter's square and a protractor fixed with its quadrant intermediate the adjacent side of said square, of a blade having longitudinally disposed 25 columns of legends designating measurements relevant to carpentry arranged to be pivotally supported on an axis in common with the axis of said quadrant, whereby said blade and the longer sides of 30 said square may cross one another when said blade is set at certain points on said quadrant, and an auxiliary rule arranged to be fixed on said quadrant in parallel relation with the longer side of said square, but 35 said auxiliary rule being calibrated to indicate lengths of higher value than those indicated on the longer side of said square.
3. In a device of the character described, a protractor having a quadrant, a blade ar-

ranged to be pivotally mounted on the axis 40 of said quadrant and removable therefrom, said blade having longitudinally disposed columns of legends designating values relevant to carpentry, and an auxiliary rule arranged to be disposed in perpendicular 45 relation with the base of said protractor and being calibrated to indicate linear measurements.

4. In a device of the character described, a protractor having a quadrant, a blade arranged to be pivotally mounted on the axis of said quadrant and removable therefrom, said blade having longitudinally disposed columns of legends designating values relevant to carpentry, an auxiliary rule arranged to be disposed in perpendicular relation with the base of said protractor and being calibrated to indicate linear measurements, and means for locking said blade against movement relative to said quadrant. 60

5. In a device of the character described, a protractor having a quadrant, an auxiliary rule arranged to be disposed in perpendicular relation with the base of said protractor and being calibrated to indicate 65 linear measurements, said auxiliary rule being calibrated on its opposite edge in an inverted manner to indicate legends designating linear measurements but of higher values than the calibrations on the opposite 70 edge, said auxiliary rule being arranged to be inverted and disposed at a point adjacent the higher values on said quadrant, and an auxiliary blade, said auxiliary blade having longitudinally disposed columns of legends 75 designating measurements relevant to carpentry.

PETER WALDO ZOOK.
